NONMETALLIC SHEATHED CONDUCTOR

Charles W. Abbott, Larchmont, N. Y.

Application August 3, 1940, Serial No. 350,194

23 Claims. (Cl. 174—116)

This invention relates to electrical conductor construction and particularly to insulated electrical conductors intended primarily for installation in buildings to form the circuit or circuits usually for lighting, power, and like uses.

One of the objects of this invention is to provide an insulated conductor or so-called "cable" construction that will be inexpensive to manufacture, of compact construction, and efficient, safe and reliable action and well adapted to meet the widely varying conditions or requirements met with in the building wiring field, illustratively in frame and like residence structures, farm buildings, and the like. Another object is to provide an insulated conductor or cable construction utilizing rubber or rubber compounds and other insulating materials in such a way as to make it possible to employ smaller quantities of rubber or rubber compound while maintaining adequate and electrically safe insulation appropriate to the various conditions under which the conductor must in practice stand up. Another object is to provide a conductor construction of the above-mentioned nature in which insulating walls of rubber or rubber compound, or the like, may be employed but in a thickness or thicknesses materially less than has heretofore been possible and to provide for such insulating walls of lesser thickness dependable and lasting mechanical protection against injury or deformation in the manufacture, handling, or use, of the insulated conductor construction.

Another object is to provide improved mechanical protection that will be easy to manufacture, inexpensive in construction, and efficient in action, for the rubber or like insulating wall or sheath of an electrical conductor. Another object is to provide mechanical protection of the just-stated character in such form that, in course of manufacture of the cable or conductor construction, deformation, indentation, distortion, or other harmful effects upon the rubber insulating wall, as such protection is applied thereto, are dependably guarded against. Another object is to provide mechanical protection of the above stated character in such form and so applied over the rubber or like wall that, during handling of the cable or insulated conductor construction as, for example, in course of installation, as well as under the conditions to which the cable construction is subjected in actual use after installation, material or harmful injury to the rubber wall or layer is reliably guarded against. Another object is to provide a cable or insulated conductor construction in which pro-

tection of the above-mentioned character for the rubber or like insulating wall or layer takes part, with the rubber wall or layer, in achieving efficiently and inexpensively the desired overall dielectric strength or insulation desired for the conductor or conductors of the construction or cable.

Another object is to provide a cable or insulated conductor construction that will have improved operating characteristics with respect to various conditions met with in installations of conductors of this type. For example, where moisture conditions are present, it has happened, in prior constructions, that elements employed in building up the sheath for the conductor or conductors act as wicks and thus wick the moisture back into the cable structure from the open ends of the latter as in outlets, causing rotting and often giving rise to fungus growths which in turn take part in both so-called "dry" and "wet" rot. Sometimes acidic conditions are met with, frequently in farm installations, as in cow barns, and acid fumes or acid-carrying moisture have been known destructively to attack non-metallic sheathed cable constructions as heretofore employed; for example, a wicking action like that just mentioned in connection with moisture carries the acidity into the internal cable structure with impairment of insulation characteristics and of mechanical protection. Also, various saturants employed on both internal and external sheathing elements have been known to be attacked or dissolved or their usefulness greatly impaired by such conditions of acidity. Another object is to provide a cable construction that will dependably and in an inexpensive way overcome or avoid such deficiencies as have just been noted with respect to prior constructions and that will afford adequate protection or resistance against such moisture, acidic, and like adverse conditions.

Another object is to provide an insulated conductor structure or cable of the above-mentioned character that will dependably function in installations of the character mentioned above without requiring metallic sheathing, or the like, and to provide a non-metallic sheathed cable or insulated conductor construction that will be inexpensive, strong, compact, electrically safe and reliable and mechanically and physically resistant in an efficient and lasting manner to the various and varying hazards to which such conductor, in such installations, might be subjected.

Another object is to provide an insulated conductor construction of the above-mentioned

character that has dependable resistance to stretch and thereby to protect the individual wires or conductors against elongation with accompanying diminution in cross-section, when the cable construction is subjected to stress. Another object is to provide a cable construction that will be simple, easy and quick for the electrician to prepare, at its end or ends, for electrical connection, and more particularly to provide for ease and speed of removal of the sheathing or sheathing elements to expose the individual wires or conductors. Another object is to provide for long lasting and dependable distinguishing or identification of polarities of the several conductors where the cable is made up as a plural conductor cable. Another object is in general and in detail to provide an improved insulated conductor or cable construction of the above-mentioned general kind.

Another object is to provide a dependable and efficient method of manufacturing insulated conductor constructions of the above-mentioned character and one that will lend itself to economic, speedy and efficient carrying out in practice and capable of high rates of production. Another object is to provide a simple and practical method of applying a sheathing element in plastic form to a conductor structure. Another object is in general and in detail to provide an improved method of sheathing a conductor or conductors.

Other objects will be in part obvious or in part pointed out hereinafter.

The invention accordingly consists in the features of construction, combinations of elements, arrangements of parts, and in the several steps and relation and order of each of the same to one or more of the others, all as will be illustratively described herein, and the scope of the application of which will be indicated in the following claims.

In the accompanying drawings in which are shown by way of illustration several of the various possible embodiments of the mechanical features of my invention,

Figure 1 is a diagrammatic representation of a sequence of apparatus illustrative of several of the earlier steps employed in my method;

Figure 2 is a similar diagrammatic representation of a sequence of apparatus for carrying out certain subsequent steps of my method;

Figure 3 is a central longitudinal vertical sectional view on an enlarged scale of part of the apparatus of Figure 2 showing its relation to the conductor being operated upon;

Figure 4 is a diagrammatical plan view of an applicator means as seen along the line 4—4 of Figure 2;

Figure 5 is a plan view of an insulated conductor or cable construction with parts progressively removed or broken away or shown in section to show the various elements and their structural interrelationships, and with other parts removed or broken away to show a possible or preferred action of "stripping" certain of the sheathing elements;

Figure 6 is a similar view showing another form of construction, and

Figure 7 is a view like that of Figure 4 illustrating another form of conductor construction.

Similar reference characters refer to similar parts throughout the several views of the drawings.

In order to make for a readier understanding

of the various features of my invention, let it be assumed that the cable or insulated conductor construction is to be installed as part of a building or household wiring system, usually of 110 volts, for lighting and analogous or related purposes; while my invention may be embodied in single-conductor form, it may be and preferably is embodied in plural-conductor form and in Figures 5, 6 and 7 of the drawings the several forms there shown, embody, by way of illustration, two conductors 10 and 11 which may be assumed, when installed, to represent or to be part of the lighting or power circuit, and hence being usually subjected to a normal operating potential difference or voltage of 110. These conductors are usually solid or single strand. To the extent that non-metallic sheathed conductor or cable has heretofore been employed in practice, the conductor or conductors thereof have embodied, usually as an initial layer of insulation, a layer of rubber or like compound, vulcanized in the form of a jacket surrounding the conductor, but it has long been considered unsafe, in such prior practices, to employ a wall thickness for the rubber jacket less than a certain limiting value, due to various and numerous factors involving elements of construction, manufacture, installation, conditions of use, and the like. In the preferred form or forms of my invention, and in so far as certain features thereof are concerned, I preferably employ a rubber jacket, preferably extruded onto the conductor and then vulcanized in any usual or suitable way, as by the known process or apparatus of continuous extrusion and vulcanization, but I am enabled very materially and with safety to reduce the thickness of the wall of such a rubber jacket and thus also to reduce the amount of rubber needed.

Thus, referring to Figure 5, and since certain of the elements applied to the two conductors 10 and 11 are preferably the same and applied in the same manner, it will suffice to describe these aspects of my invention only with respect to conductor 10 onto which is extruded a rubber jacket 12 and vulcanized; jacket 12 is preferably of lesser wall thickness than has heretofore been possible, for example, a reduction in wall thickness on the order of 40%.

Among the reasons why, in the processing or manufacture of cable or conductor of this general type according to prior constructions and methods, reduction of rubber wall thickness was not carried out, is in the fact that the insulating materials superimposed upon the rubber, usually immediately after vulcanization, have been of a nature and have been applied under such conditions of pressure or tension that harmful deformation of the rubber, usually still in a somewhat soft condition, would result. Also, as is usually the case, the conductor is of solid metal so that any bending or flexing thereof during various stages of processing would tend also to effect deformation or distortion of the rubber jacket, and in various ways, such as in a direction outwardly through the rubber or like compound of the jacket, due to the direct internal action thereon by the conductor itself.

Having applied the jacket 12 of rubber, or like compound, for example in the manner above indicated, as above noted also, I apply thereto a coating, indicated at 13, of a suitable material or compound, preferably capable of being applied in liquid or semi-liquid form, but which, upon becoming set, is dry, flexible, and preferably also

somewhat elastic, and has preferably also good or suitable adhesion to the rubber jacket 12. The material, compound, or composition, employed to form the coating or layer 13, may vary widely and preferably and illustratively I employ a lacquer whose ingredients are suited or selected, in a manner known in the art, according to the manner or method of application thereof to the element 12 and to the ultimate characteristics, such as those above-mentioned, desired. Thus, in the fields of lacquers and liquefiable synthetics alone numerous compositions of various ingredients are available for this purpose; such compositions are referred to in certain of the claims hereof as being of the lacquer class. I preferably and illustratively employ a lacquer having for its base a cellulose derivative, preferably cellulose nitrate, and having included therein a suitable solvent or solvents and a suitable plasticizer or plasticizers. The application of the coating material may be carried on in any suitable or known way and when the solvent or other volatile constituents (in the case of lacquers) are evaporated or driven off, the material becomes set with the desired degree of hardness and thickness of coating as well as sufficient flexibility and elasticity thereof to be somewhat yieldable and stretchable, thus to avoid cracking, chipping or crazing. The resultant coating 13, which may be of a thickness on the order of several thousandths of an inch, is also, in preferred form, quite smooth and slippery, its exposed surface being of low coefficient of friction in coaction with other material which I may use superimposed upon or about the layer or coating 13.

Preferably, the material of the coating 13 is of the type, such as the above-mentioned lacquer, that sets in response to the application thereto of heat or whose rate of setting is increased in response to the application of heat; in such way, I prefer to apply the coating material to the rubber-jacketed conductor while the latter with its jacket retains or has a heat content derived from the step of vulcanization.

Thus, as diagrammatically shown in Figure 1, I prefer to use a continuous vulcanizer 14 through which the rubber-jacketed conductor 10-12 is drawn at a suitable speed, a speed which may be on the order of several hundred feet per minute; the vulcanizer 14 comprises a pipe-like chamber of suitable length charged or supplied with steam at suitable pressure and temperature so that the conductor emerges therefrom with its rubber jacket 12 practically or completely vulcanized; any suitable form of continuous vulcanizer may be employed and, as is usual in practice, it is preferably associated directly with an extrusion head or machine which extrudes the rubber jacket onto the wire.

Emerging from the vulcanizer 14, the still hot 60 jacketed conductor, the temperature or heat content of which may at this stage be altered, if desired, by a suitable heat exchanger (not shown) passes through an applicator 15 in the form of a suitable device or chamber containing the coating material, such as lacquer, supplied thereto as from a tank 16 and provided with suitable means, such as a rubber element or elements, at its right-hand or outlet end to regulate or fix the thickness of the coating with which the rubber-jacketed 70 conductor emerges therefrom. The heat content of the jacket 12 or of the wire 10 or of both heat-treats or sets the thus applied coating 13, insuring also a good bond between it and the rubber to which, it will be noted, the coating material 75

is applied while the rubber surface is still virgin and in effect open-pored or in a condition analogous to porosity.

The coating is strong, relatively tough, and affords mechanical protection and reinforcement to the rubber jacket 12. Moreover, and preferably, I include in the compound of which the coating 13 is formed, such as lacquer, suitable coloring materials, preferably in the form of pigments and, where a plural conductor cable is to be constructed, as the two-conductor cable of Figure 5, the pigment employed in the coating on rubber-jacketed conductor 10 is different from the pigment employed in that of rubber-jacketed conductor 11, thus to distinguish the several conductors in the cable. These pigments may be selected according to existing color codes and thus, in a two-conductor structure like Figure 5, the coloring or pigmentation of the one coating may be gray and of the other may be black.

In a structure like that of Figure 5 and for reasons later set forth, I prefer next to apply over the coating 13 a layer or coating of a suitable wax-like material; in Figure 5 that coating is indicated at 17 and it is preferably applied as a step following the step of applying and setting the coating 13.

Thus, I may provide an applicator chamber 18 through which the conductor structure passes and which contains a suitable wax-like material in heated and hence substantially liquid form, thus coating the conductor element, any suitable means being provided, if desired, to determine, as by a yieldable wipe, or the like, the thickness of the layer picked up by the conductor element as it passes through the bath in the applicator 18.

Since, in the preferred process, where the conductor continues to move at the substantial speed at which it is extruded and vulcanized, the conductor element emerges from the coating applicator 15 in a still heated condition even though some of its heat content has been dissipated in setting the coating 13, and hence I prefer appropriately to regulate or interrelate the characteristics of the wax-like material and the temperature or heat content and speed of the conductor element. Thus, for example, I may regulate the heat content of the conductor element by a suitable heat exchanger (not shown) interposed between the applicators 15 and 18 and thus suit it to the characteristic of melting point and viscosity of the material in applicator 18, it being noted that when the conductor emerges from applicator 18, the wax-like material should set relatively quickly rather than be kept in such a state of fluidity by the heat content of the conductor element as to cause uneven distribution of the coating, particularly where the conductor element moves in a general horizontal direction.

Or, as in the preferred step, I may achieve such a suitable interrelation of factors by utilizing a wax or like compound that has a melting point sufficiently high relative to the temperature or heat content of the moving conductor element that setting at the desired rate and even distribution or thickness of coating are achieved. Also and preferably I prefer to use a wax compound of appropriate "body;" for example, I may employ a wax loaded with zinc stearate, having a melting point on the order of 160° F., somewhat higher than the temperature of the jacketed conductor element as it enters 75 the applicator 18. The loaded wax has suffi-

cient "body" so that, emerging from the applicator 18, as a liquid coating on the conductor element, it does not appreciably migrate or flow and hence uniformity of thickness during and after setting results.

The wax compound in applicator 18 is preferably circulated therethrough in heated and liquid condition by any suitable means, such as a pump 20, connected in series by suitable piping with the applicator 18 and a tank 21 which is provided with any suitable heating means diagrammatically indicated at 22.

If desired also setting of the wax coating, which may have a thickness on the order of 0.015 inch or cooling of the coated conductor element may be effected by a suitable heat exchange device 23.

Subsequent steps are effected at a lower rate of speed of movement of the conductor element and hence it is preferred now to reel up the conductor element 10-12-13-17 and in this connection the cooling by heat exchanger 23 may be used to facilitate immediate reeling up. From such reels, the element is run off and during continuous movement thereof, in the preferred form of my method, I perform a succession of operations diagrammatically indicated in Figure 2, and of which the first comprises winding about the element and hence onto the last-applied coating, in the above instance being the wax coating 17, a band or tape-like member 24. The latter is preferably of paper and of suitable thickness and width, illustratively a thickness of 0.0025 inch and a width of $\frac{1}{4}$ " and it is wound helically preferably with a small overlap.

Any suitable apparatus diagrammatically indicated at 25 may be employed for thus wrapping the member 24 as the conductor element continues to move in a direction toward the right as viewed in Figure 2; the speed of such movement may be on the order of 60 feet per minute. Leaving the wrapping machine 25, the conductor structure enters a suitable machine or apparatus 26 which applies to the structure and onto the last-applied layer of material, in the illustrative embodiment being the paper wrap 24, a continuous helix of a cord-like element 27 wound at a pitch to leave a suitable spacing between successive turns somewhat analogous to a form of screw thread. Member 27 may be substantially round in cross-section and is preferably made of twisted paper, being thus a form of so-called paper cord. The pitch of winding may be such, illustratively, as to give a spacing on the order of $\frac{1}{8}$ " from center to center of successive turns, thus forming a helical rib lengthwise of the structure and forming a helical space.

The rib 27 may be made of relatively tough or strong construction and is preferably wound with sufficient tension or tautness as to cause each turn to resist shifting thereof relative to the underlying supporting core structure. The tenacious and relatively tough coating 13 of lacquer supplemented by the paper or layer 24 forms a dependable foundation for this helical rib 27 and the coating 13 in coaction with the covering 23 also protect the rubber jacket 12 against detrimental distortion or compression under the winding tension of the rib member 27.

Continuing its movement toward the right, the structure, now with the helical rib 27 about it, passes through an applicator apparatus, gen-

erally indicated by the reference character 28, and which, where the material to be next applied to the conductor structure is a thermo-plastic having preferred characteristics as later described, preferably takes the form shown in Figures 2, 3 and 4.

Thus, the apparatus 28 may comprise a tank 30 of suitable capacity and depth to contain the plastic material and provided with suitable means 10 for insuring its application to the conductor structure. The latter may enter through a suitable bushing, or the like, 31 in one end wall of the tank 30 and pass through a suitable device 32 suitably related to the opposite end wall. The device 32 preferably comprises an internally tapered tube-like element having a land or portion 32a at its exit or right-hand end (Figure 3) that is of uniform inside diameter somewhat less than the outside diameter of the helical rib 27; for example, if the outside diameter of the rib 27, in a structure utilizing No. 14 B & S gage wire for the conductors 10 and 11 is 0.187 inch, the inside diameter of the straight portion 32a is about 0.175 inch to 0.180 inch. With this preferred restricted exit throat in element 32, the conductor structure drawn therethrough is subjected to some degree of compression, particularly the turns of the helical rib 27, and other actions take place as later described.

30 To the left of the straight restricted portion 32a, the internal diameter of the tube-like applicator member 32 increases, preferably gradually, thus to form by its tapered internal walls guides for the plastic material, as is later described, and 35 also guides to enter the turns of the helix 27 neatly and snugly into the restricted throat portion 32a.

Member 32 is mounted in any suitable manner to the end wall of the tank 30 and preferably detachably; thus, it may be externally threaded at its left-hand end and threaded into a collar or bushing 33 in the end wall of the tank.

As the structure is drawn through the tank 30, the plastic compound is picked up or applied to the rib structure and the latter with the compound enters the member 32 where the plastic material is indicated at 34. If desired, suitable means may be employed to insure the application of the material 34 to the moving conductor structure so that, for example, the application of the material does not have to depend too much upon the depth or amount of material in the tank. For example, I may employ suitable rotary means, such as two spaced disk members 35, 36 (Figure 4) fixed to a shaft 37 driven by any suitable means, such as a motor 38, at a suitable speed and positioned relative to the bottom of the tank and the line or axis of movement of the conductor structure, somewhat as is indicated in Figure 2, so that at least portions of the rotary members 35 and 36 are always submerged and as they rotate they pick up and wipe onto the axially moving conductor structure suitable quantities of the plastic material 34.

The material 34 is preferably a thermo-plastic that is preferably quick-setting and, at temperatures usually encountered in the storage or installation or subsequent use of the finished cable construction, is non-migrating, relatively tough, yieldable or resilient; such temperatures might range from around 30° F. to 180° F. It preferably has other characteristics later pointed out.

For example, this composition or compound may comprise asphalt, bitumen, coal tar pitch, petroleum pitch, vegetable stearine pitch, animal

stearine pitch, or like hydrocarbonaceous materials, preferably in suitable combination or combinations with suitable fillers, preferably inert mineral fillers, such as limestone, siliceous materials, like mica, fillers like talc, slate flour, asbestos, diatomaceous earths, and the like, Nylon or glass fiber flockings, etc.

An illustrative mixture or compound comprises by weight 75% of oxidized petroleum asphalt, 10% of slate flour, 10% of Muscovite (flake) mica, and 5% of Biotite mica. By way of further illustration another compound may comprise by weight 50% of oxidized petroleum asphalt, 30% of inactive asphalt, 10% of Muscovite mica, and 10% of fine divided asbestos. Another 15 illustrative compound may comprise by weight 70% of oxidized petroleum asphalt, 20% of slate flour and 10% of shredded mica.

Such a mixture or compound is placed in the tank 30 (Figures 2 and 4) where it is preferably maintained in a suitable plastic or appropriately workable state preferably by heat, the tank 30 having associated with it any suitable heating means diagrammatically indicated at 40 and preferably also the tube-like member 32 is heated by any suitable means, such as a jacket or electric heating unit, or the like, diagrammatically indicated at 41. The temperature at which the material is maintained preferably is related to the composition and hence characteristics of the thermo-plastic material 34 and to related factors, such as the reaction of the material of the helical rib 27 and the material of the wrap 24 and of other elements as is later pointed out. Thus, utilizing one of the above-mentioned illustrative compositions for the material 34, its temperature when in the tank 10 and while operated upon by the tubular member 32 is on the order of 300° F., it being noted that a slightly higher temperature is utilized where the percentage of filler is higher. At such a temperature, the mass is suitably workable to take part in the actions of application about to be described, particularly at the speed of movement of the conductor structure or core, and moreover, does not detrimentally affect the materials, illustratively paper, of the helical rib 27 and the underlying wrap 24, nor does it affect, as by over-vulcanization, the rubber jacket 12.

The mass of material in the applicator tank 30, though relatively dense or thick and having substantial body, has portions of it transferred steadily onto the moving conductor or core structure, illustratively by the rotating applicator members 35 and 36, where the conductor or core structure is not submerged in the plastic mass itself. This transfer or application may and frequently does take place with some non-uniformity in that over-excess of the plastic material may be thus transferred. But the core structure with the plastic material wiped or smeared or otherwise transferred onto it enters the tapered interior of the device 32 (Figure 3), the tapered or progressively restricted walls thereof compacting or forcing the material inwardly toward the axis of the conductor structure, particularly in the tapered region just to the left of the straight or land portion 32^a above-described. As the material is thus pressed inwardly against and about the structure, the relatively rigid and non-migrating rib structure 27 acts like a continuous vane to move the compressed material along with the conductor structure and to resist displacement or migration thereof relative to the moving conductor structure, at least so much of the surrounding mass as occupies the continuous helical

space formed by the helical rib 27. In effect, the helical rib, after the progressively restricted space within the member 32 packs the material against the base of this helical space, specifically against the wrap 24, forces or pulls the material along with the movement of the conductor core structure and thus insures that that helical space is completely filled up.

As the parts enter and move through the straight or land portion 32^a (Figure 3), a combined compressing, smoothing and wiping action takes place, preferably also, as above noted, to an extent to somewhat compress or diminish the outside diameter of the helical rib 27. In the course of this action the material is compacted against the wrap 24, into any interstices that may exist in the rib structure 27 itself or between it and the wrap 24 and also against or onto or into the now somewhat flattened external face of the helical rib, emerging from the member 32 as a smooth cylindrical element substantially free from undulations and in appearance being of the color of the plastic material 34 itself, usually black, with the helical rib 27 hardly or not at all discernible due principally to the impregnation or covering (in an outer layer) of its material by and with the plastic itself. The above described actions are preferably facilitated by maintaining the temperature at a suitable level as by the heater 41 above described. The plastic material, filling the helical space, appears as a helically distributed band or ribbon of substantial thickness, and as such an entity is indicated in Figure 5 by the reference character 42.

While the just described physical actions are taking place, other actions, in this preferred method and form of conductor structure, also take place. Thus, the material of the helical rib 27, preferably of twisted paper, becomes impregnated by the plastic material and a similar impregnation of the wrap 24, also preferably of paper, takes place in a direction from its external surface toward its internal surface. The above-described magnitude of temperature, it might be noted, does not detrimentally affect the paper of the just-mentioned elements.

The heat content of the plastic material, however, and as soon as it is brought into thermal contact with the wrap 24, acts upon the wax of the coating 17 which is heated sufficiently to impregnate the wrap 24 in a direction from its interior face or surface toward the outer face, and thus I may achieve impregnation of the wrap 24. Though thereby the wax of the coating 17 may be somewhat diminished, there is enough wax left either in the coating or at the inner surface of the wrap 24 to function, in a sense like a lubricant, to insure ease of relative movement or slippage between the rubber-jacketed structure or core and the wrap 24 and the parts that are external of the latter, though it will be understood that even in the complete absence of wax or of a waxy surfacing or impregnation of the wrap 24, the coating 13, preferably and illustratively of lacquer, as above described, preferably has a smooth and slippery external surface which by itself facilitates such relative slippage or movement, as in bending or curving the conductor structure either in subsequent stages of manufacture or thereafter. Also, it will be understood that if desired I may initially impregnate or treat the material of the wrap 24 as by use of a suitable wax or by the use of a suitable saturant; in such case, I may or may not, as desired, utilize a wax coating like coating 17. The structure

emerging from the applicator apparatus 28 (Figure 2) next has applied to it a covering preferably in the form of a band or tape-like element 43 preferably of paper, preferably employing any suitable form of tape wrapping machine, as is diagrammatically indicated at 44 in Figure 2. This paper tape 43 is preferably very thin and may be, for example, made of a rope-sulphite paper preferably in a width commensurate with the width of the wrap 24 and applied preferably with a slight overlap, directly over the structure which, as above noted, and as indicated in Figures 2 and 3, presents an external substantially cylindrical surface of plastic material. Onto the latter the wrap 43 is applied and preferably before the mass has materially cooled off and hence is still at the temperature at which it leaves the applicator apparatus 28.

It will be understood, however, that I may, in any suitable manner, as by a heat exchanger (not shown) suit the temperature of the conductor or core structure, now embodying the thermo-plastic, to the desired conditions or circumstances of application of the wrap 43.

For example, I prefer to have the mass 42 (Figures 2 and 5) at a temperature such that there is adhesion or uniting between the tape 43 and the element 42 and preferably also impregnation of the former by the latter, thus bringing about an action similar to that above described in connection with the tape or wrap 24; where the temperature of the compound or material in the tank 30 is on the order of 300° F., the temperature, by way of illustration, at the time of the application of the paper tape 43 may be somewhat less and hence on the order of 280° F.

Next I prefer to apply a coating of wax, indicated in Figure 5 at 45, and this application may be made in any suitable way as the conductor or core construction continues to move along. Thus, the wax-like material employed may be similar to that used in making the coating 17 and a similar form of apparatus may be employed, comprising, for example, an applicator chamber 46 (Figure 2) suitably supplied with the wax material at suitable temperature, as, for example, by means of a pump 47 serially connected through suitable piping with the applicator 46 and with a tank 48, suitable heating means diagrammatically indicated at 50 being employed to keep the wax at a suitable temperature and a suitable degree of fluidity.

The wax compound may be of any suitable composition and may be loaded or otherwise compounded so that it will have suitable body so that, in relation to the heat content or temperature of the core or conductor structure onto which the wax coating is thus applied, the wax coating does not appreciably migrate or flow, thus to achieve uniformity of thickness during and after setting of the coating. But preferably coating 45 is relatively thin and in such case, such factors as "body" characteristic may be given less consideration.

Also, it will be understood that if desired I may initially impregnate or treat the material of the wrap or tape 43 as by use of a suitable wax or other suitable saturant; in such case I may or may not, as desired and depending upon circumstances, utilize a separate wax coating 45, 70 it being noted that in such case the heat content of the core structure, principally of the thermo-plastic element 42, may take part in effecting a softening or melting of the saturant, where a wax-like material is used, to reaccommodate the 75

impregnated tape 43 with its saturant to its new helical condition and preferably also to effect a binding or adhesion between the material or element 42 and the band member 43.

- 5 Usually and preferably, the conductor structure is now reeled up and in this connection a suitable heat exchanger (not shown) if desired may be used to reduce the heat content of the structure, and from such reels the conductor element may now be further processed. Onto the core thus formed I now apply an outer covering element 51 (Figure 5) which is preferably braided on, as by using cotton braid, but preferably, because of factors later mentioned, after first applying a suitable sheet material like paper, as indicated at 49, and where the cable is to contain more than one conductor, illustratively the two conductors 10, 11 of Figure 5, two such cores are encased side by side first in the sheet material 49 and then in the sleeve or tube-like braid formation 51, the several cores being together run through a suitable machine to apply first the sheet material 49 and then the braided covering 51 thereover. The element or material 49 may be applied in the form of a helix or wrap with a suitable overlap or it may extend longitudinally with its two longitudinal edge portions overlapped; crinkled kraft paper is preferably employed.
- 10 Where two such cores are thus assembled, there extend lengthwise of them two valleys formed by the side by side relationship of the two cores. Due to such features of construction and steps of operation as those above described, the outside diameters of these core structures are materially less than in structures heretofore employed, being each, in the illustrative embodiment, on the order of 0.180 inch in diameter, and these valleys are relatively small. Into preferably only one of them, such as the upper one as seen in the plan view of Figure 5, I run a cord element 52 which has substantial tensile strength for its small cross-section and which preferably also is non-porous or non-cellular and devoid of a wicking action; a suitable material for this paper is a cord or yarn made of woven or twisted synthetic fiber, preferably of synthetic or artificial silk, such as the kind known and available on the market by the trade name "Nylon." Even in the small cross-section appropriate to substantially fill in this small valley, Nylon yarn has a tensile strength on the order of 150 pounds. It is run into the valley along with the two conductor cores, entering the machine that applies the paper sheath 49. In the other valley I prefer to employ a less expensive material and here a small-cross-sectioned yarn or cord or paper or jute 53, suitably impregnated or saturated, may be employed.

The braided covering 51 having been completed, I now subject it to suitable treatment in any suitable way, as by impregnation with suitable compounds or materials to give it the desired moisture-proof, fire-resistant, mold-resistant, and like characteristics. Thus, I may run the structure successively through saturating baths, for example, first through a tank containing the saturant that gives the braid covering 51 moisture-proof qualities, then through a tank to give it flame-resistant and moisture-proof qualities, the sheath 49 acting as a barrier, dam or baffle to block penetration of the braid-impregnating compound beyond the thickness of the braid itself or to block migration of the compound to or into other parts of the structure.

Lastly, I prefer to apply, after drying or setting of the just-mentioned saturants, a final coating, indicated at 54 in Figure 5, of a material preferably of the general characteristics and composition like that of which the coating 13 above-described may be made, excepting that, where I employ a pigment or coloring element as an ingredient, I prefer to use aluminum powder as a pigment. Thus, the coating 54 may be in the form of a pigment-carrying lacquer, preferably compounded to be quick-drying so as to facilitate "air drying," though it will be understood that any other suitable means may be employed to effect relatively quick setting of the coating. Such a coating though applied in a relatively thin layer is resistant to and substantially impervious to acid-bearing fumes, such as those earlier mentioned above, it films over and thus covers or seals, with a relatively tough stretchable or resilient skin interstices, and the like, that frequently occur in the braid structure and its saturants, it is resistant to or unaffected by high temperatures liable to be met with in practice and thus counteracts migration of fillers or saturants in the underlying braid, it being noted that frequently such fillers or saturants have relatively low melting points or become flowable at relatively low temperatures. Thus, a clean non-tacky long-lasting easily handled structure results. Such a coating is impervious to moisture, is strongly resistant to weather, and the like, and adds protection against the effects of the sun. Also, the materials of which it is made or compounded lend themselves easily and inexpensively to coloring as by pigments, and thus I am enabled to give the final cable structure a neat and attractive appearance in contrast to the crude appearance of structures heretofore employed, a factor which has limited its scope of practical application. Also, such a final coating forms a good base for ordinary types of paints, and thus the cable structure may be painted, for example, when installed.

The construction I am enabled to embody in materially smaller cross-section than the cross-section of cable conductors heretofore employed; for example, in the two-conductor structure of Figure 5, utilizing two No. 14 wires, the dimension along the major axis may be on the order of $\frac{1}{8}$ " less than the dimension along the minor axis on the order of $\frac{1}{16}$ " less than the corresponding dimensions in prior commercial types of construction. Thus, also, substantial economies in shipping weight, less bulk and greater facility in handling and greater range of usefulness, such as in passage through smaller holes or entry into more restricted spaces, in course of installation, result. Also, less "crowding" of conductors in outlet boxes, and the like, may be had.

The construction is also less expensive and the method lends itself to commercial operation on a quantity production scale. For example, the application of the material 34 in Figures 2, 3 and 4 is simply and dependably carried on; the helical rib structure 27 in coaction with other elements insures proper application of the material and makes possible the employment of inexpensive compounds and compounds of low temperature characteristics. Thus, also, considerable "loading" of the compound, as by such fillers or loaders, preferably inorganic, as those mentioned above, with attendant advantages, may take place even though the compound may as a result be relatively stiff.

In the cable structure the element 42 is yield-

able or resilient at ordinary temperatures met with in installation and does not migrate or flow, even at the higher temperatures met with. Being present in the form of a helix in the helical space formed by the rib structure 27 and each turn thereof being well backed up by the relatively tough or rigid adjacent turns of the rib structure 27, the structure offers dependable mechanical resistance to mechanical injury, such as penetration by nails, or the like, any tendency to displace the element 42 or part of it (see Figure 5) being strongly resisted by the rib structure 27 and other elements that take part in confining the material. The rib structure 27 itself offers strong resistance to mechanical injury and is well adapted to veering off instruments like a nail, an action in which the compound of the material 42 may take part or which it may assert of itself.

The pliancy or elasticity of the material of element 42 facilitates bending or curving of the structure and in its preferred form its penetration into and adhesion to its directly associated elements, such as the helical rib 27 insure against opening up or the creation of cracks or fissures at the longest radius of curvature when the structure is bent and the rib structure 27 insures maintenance of concentricity or roundness of the built-up structure. Preferably, also, ease of bending or curving is contributed to by relative ease of sliding or slippage between the interior face of the wrap 24 and the element underneath it, such as the coating 13 which is preferably slippery, as above-mentioned, or such as the wax coating 17; in such bending or curving, also, relative ease of slippage between the inside face of the element 49 and the elements contacting therewith, such as the paper wrap 43 or the wax coating 45, is preferably present.

Also, I achieve safety and facility of manipulation or handling in installation. The tensile strength of the element 52, even though of small cross-section, resists tensile stresses to which the cable structure may be subjected, as by "pulling," and thus resists elongation of the copper conductors and accompanying reduction in cross-section thereof. Also, the tensile strength of element 52 makes it possible for it to function as a dependable rip cord for unsheathing the outer elements of the structure, as by causing the cord 52 to tear, cut or rip the coverings 49 and 51, as when the ends of the cable structure are to be exposed in turn to be "stripped" to expose the wires themselves.

In this latter connection, due to characteristics of the material of element 42 and coactions thereof with other elements, some of which are mentioned above, the relatively strong and tough helical element 27 acts as a "stripping" element, for its extreme end need only be grasped and pulled in the general direction of the axis of the conductor, resulting in a sort of unwinding action but accompanied by the removal, with the element 27 and as a unit therewith, of the inner wrap 24, the outer wrap 43, and the compound element 42, the adhesion of the latter to the former and to the helical element 27 causing them all to be removed cleanly, and at substantially the same speed or quickness with which the helical rib 27 itself could be disassembled by a pull generally in the above-mentioned direction. Thus, element 27 parts sheet elements 24 and 43 either at their overlaps or by tearing and parts the turns of helical mass 42; the coating 13, when and where employed, becomes exposed 70 and where it carries a coloring or pigment polar-

ity or like identification of the individual conductor is at once present; the rubber jacket 12 is easily stripped off in known manner and thus the bared conductors are available for making electrical connection.

In installation high protection against moisture, fungi or mold, acid-bearing fumes or vapors, and like effects is achieved. Wicking action is dependably resisted and the small dimensions and compactness of construction with resultant greater ease and dependability of filling the valleys guard against the presence of hollow spaces along which infiltration of moisture or acid-bearing air or gases might otherwise take place. Wicking action by way of such elements as members 24, 27 and 43, as to moisture, or the like, is well guarded against, even though these elements may be made of an organic material like paper, by the coverage or impregnation thereof, or both, by the compound or material of element 42, while the same or similar effects guard against movement of moisture, or the like, in a radial direction inwardly through these elements, the material of element 42 itself being impervious to moisture and, as above indicated, comprising also preferably inorganic elements and being inert. In effect, the structure also adequately and permanently encloses or seals the rubber or like material of the jacket 12 of the conductor or conductors against passage or infiltration of moisture, fumes, fungi, mold, or other deleterious elements or effects. If desired, also, rodent repellants in the form of suitable saturants or ingredients may be incorporated in the elements 24, 27 and 43 or compounded with the material of element 42.

The above-described construction and method lend themselves to modification or variation. Thus, for example, and returning to Figure 6, the material of element 42 above described may be interrelated with other elements, such as an underlying helical element 56 of fiber-like strands of glass, preferably of a diameter or degree of fineness just large or heavy enough to permit them to become interwoven, or intermingled, or matted or felted together in a manner analogous to glass wool, preferably with a binding material, such as a phenolic condensation product. Element 56 occupies part of the depth of the helical space between the helical rib element 27 and may be applied in any suitable manner, preferably by means of a separate carrier element, such as paper, which may comprise a paper wrap 24^a to which the glass fiber element 56 adheres or is bound, as by the above-mentioned binding material. The rest of the depth of the helical space may be filled with a material like the material 34, above-described, and of which the above-mentioned element 42 is made, being shown in Figure 6 at 42^a. Depending upon its composition, the application of element 42^a proceeds preferably in the manner above described, as in connection with Figures 2, 3 and 4, and preferably under conditions such as cause it to be pressed into and impregnate such tape or paper elements with which it contacts and to become also adhered to the glass fiber element 56; or, to illustrate another form which the material 34 may take for making up a helical element of the general shape of element 42 of Figure 5 or for making up an element like element 42^a of Figure 6 in association with a material like fiber glass, it may comprise suitably small particles of suitable material bound together and preferably also bound to the parts or surfaces of the conductor core structure with

which it is in engagement, an illustrative material comprising vermiculites in suitably divided form, usually granular or flake-like, the above-mentioned binding being achieved by a suitable binder which may take the form of a phenolic condensation product, any suitable non-conductive plastic cement, such as rubber cements, latex, or the like. In its application, as by an apparatus like that indicated in Figure 3, the helical rib element 27 preferably takes part in insuring, in coaction with the interior faces of member 32, the application of the mass of vermiculite particles with their binder, much in the same manner as was described above in connection with Figure 3. Otherwise, the procedure and the preferred coacting elements of the construction are as those described in connection with Figure 5, it being noted that the mass of bound-together vermiculite particles has pliancy and flexibility, individual particles stretching or expanding or contracting.

With a construction like that of Figure 6, stripping off, as by pulling upon the end of the helical element 27 at the end of the conductor structure 25 may be effected with the facility described above in connection with Figure 5. Such facility of stripping and also certain of the earlier above-mentioned advantages of my invention may be achieved with a structure like that shown in Figure 7 where the helical space formed by the helical rib element 27 is occupied entirely by a material like the fiber glass element 56 above-described, the binding element of which, or a suitable similar binder, preferably binding elements 35 24^a, 56, 43 together and to the helical rib element 27. Pulling the latter at its end thus strips off a composite but unitary helix made up of these elements, thus quickly exposing the underlying element or elements.

40 Where a mass of particles like vermiculite is employed, the material of the particles is preferably inorganic and substantially inert chemically; where fiber-like material, like the glass fibers of element 56, is employed, the material thereof 45 preferably has similar characteristics, and, moreover, both materials, being inorganic, do not encourage the formation or growth of mold. Fiber-like elements of mineral base, such as Nylon, may also be employed. In applying such 50 materials, the application proceeds preferably with the accompaniment of heat which may be applied in any suitable manner to drive off moisture that may be related to the materials as, for example, in interstices between fiber-like elements or between particles and also where, as is 55 preferred, an inorganic heat-responsive binder is employed. Thus, or in any other suitable manner, heat treatment may bring about such interactions as impregnation of the tape-like elements 60 24 and 43 and the rib structure 27 with wax-like material, such as the material of coating 17, or the saturant (where one is employed) in such elements as elements 24, 27 and 43, or a binding together, as mentioned above in connection with 65 Figure 7, to facilitate stripping off of the various elements as a unitary helix, as is preferred.

Recurring to Figure 1, subsequent to the step of applying the coating 13, as by the apparatus 15-16, and just before completion of setting of the applied coating, particularly where it takes the form of a lacquer, I prefer to apply thereto a material comprising small particles or flakes, indicated at 13^a, preferably mica of suitable and preferably very small mesh; any suitable means (not shown) such as a "head" or "chamber" con-

taining the material and through which the coated conductor core is drawn, may be used to make the application. The particles partially embed themselves in the outermost portions of the coating, it being noted that in the preferred manner of applying a heat-responsive coating, namely, to utilize the heat content of the rubber jacket and/or of the conductor therein, heat treatment of the coating material takes place in a direction radially outwardly so that the outer portion or skin of the coating is in a condition receptive to these applied particles even though inner portions thereof are set; protruding portions of the particles, after completion of setting of the coating, afford additional and better adhesion of the wax-like material applied thereafter, as by the applicator 18. Also, such particles provide a mechanical insulation against possible tackiness of the coating, and thus facilitates handling of the structure should such handling become necessary at that stage of the preferred form of process.

In the completed conductor structure, as in Figures 5, 6 and 7, these particles 13 toughen the coating and when made of mica contribute a factor of lubrication to still more facilitate ease of relative movement between the coated internal core structure and the parts overlying it, as when bending or curving the conductor structure. Such an external application of such particles does not detrimentally affect color elements or pigmentation of the coating material.

Thus, it will be seen that there has been provided in this invention a conductor construction and a method of processing the same in which the various objects hereinbefore noted together with many thoroughly practical advantages, are successfully achieved. It will be seen that I am enabled to combat effectively the various elements which in prior practice have been found to have detrimental effects upon materials as heretofore employed; thus, for example, entry of moisture, or the like, into the structure is counteracted in a dependable, inexpensive, compact and mechanically and electrically efficient structure, utilizing therein preferably inorganic non-hygroscopic elements and reliably rendering non-hygroscopic such other elements as are for various other reasons of organic material, such as paper. It will be seen that the construction is well adapted to meet the varying conditions of hard practical use.

As many possible embodiments may be made of the mechanical features of the above invention and as the art herein described might be varied in various parts, all without departing from the scope of the invention, it is to be understood that all matter hereinabove set forth, or shown in the accompanying drawings is to be interpreted as illustrative and not in a limiting sense.

I claim:

1. An insulating conductor construction of the character described comprising a conductor core structure having thereabout a helical tape element, a rib element of substantial thickness and tensile strength and extending helically at substantial pitch about said core structure and tape element, thereby providing a helical space thereabout of substantial radial dimension and whose bottom comprises portions of said tape element and whose side walls are defined by the sides of adjacent turns of said rib element, pliant sheathing means filling said helical space and by the bottom and side walls thereof being given

a helical form, means binding said helical sheathing means and said helical rib together and upon both sides of the latter to form therewith a substantially continuous insulating and mechanically protective jacket of substantial thickness, and removable covering sheath means thereover, the tensile strength of said rib element being sufficient, when said covering sheath means is removed and upon subsequent pulling the end of said helical rib element in the general direction of the axis, to break the bond between said helical sheathing means and said helical rib element on that side of the latter opposed to the direction of pull on the rib element and throughout as many turns of said helical rib element and helical sheathing means as correspond to the axial length of said core structure to be bared, said binding means having a strength normally to hold said helical sheathing means and helical rib element bound together on both sides of the latter during flexing of the entire conductor construction and also bound together, as said rib element is pulled, on that side of the rib element in the direction of pulling of the latter, thereby to remove said helical sheathing means substantially as a unit with said rib element and to expose said core structure.

2. A conductor construction as claimed in claim 1 in which said helical sheathing means comprises a mass of material that is pliant at the usual range of temperature of operation or installation of the conductor and which at higher temperatures has sufficient mobility to impregnate impregnatable fibrous elements, said tape element and said rib element being made of impregnatable fibrous material, said binding means comprising portions of said mass flowed under heat into said tape and rib elements.

3. A conductor construction as claimed in claim 1 in which said helical sheathing means comprises a mass of intermingled fibers of non-conductive material in said helical space and by the latter given a helical form, with a binder binding said fibers together, whereby upon pulling said rib element the helically shaped mass of bound-together fibers is removed turn by turn with said rib element.

4. A conductor construction as claimed in claim 1 in which said helical sheathing means comprises at least two superimposed helical layers accommodated in said helical space, one layer comprising a mass of fibers of insulating material and the other layer comprising a mass of pliant material, said binding means binding both layers to said helical rib element whereby the latter, upon being pulled, removes both layers with itself substantially as a unit.

5. An insulated conductor construction of the character described, in combination a conductor core structure comprising a conductor and a rubber jacket, said core structure having thereabout a non-conductive sheet-like material overlying said rubber jacket, a rib element of substantial thickness and of a non-conductive material resistant to compression extending helically about said sheet-like material and forming an open winding to provide a helical space, the turns of said rib element having a tightness of winding appropriate to resist shift relative to one another and said sheet-like material coacting to protect the rubber of said jacket against the tightness of winding of said rib element, means comprising a tough pliant non-flowable insulating mass compacted into said helical space, a non-conductive sheet material overlying said insulat-

ing mass and said helical rib element, said insulating mass being confined, and mechanically insulated from other elements, by said first sheet-like material, said rib element, and said second sheet material, and a non-metallic casing snugly encompassing and confining the structure and bridged across the turns of said rib element and by the latter and said insulating mass held against material movement inwardly toward the axis of the structure, said casing backing up and reinforcing said last-mentioned sheet material in confining said pliant non-flowable helical mass whereby the insulating elements about the rubber jacket protect the latter mechanically against crushing, deformation, and the like and displacement, as by an implement, of said mass in said helical space is resisted by its inherent characteristics and by its confining elements including said helical rib element.

6. An insulated conductor as claimed in claim 5 in which said mass comprises a material that is pliant and non-flowable at operating and installation ranges of temperatures and that is relatively flowable and has adhesive qualities at higher temperatures, said helical mass, said rib element, and said two sheet materials being bound together by the material of the mass itself under heat treatment at said higher temperatures.

7. An insulated conductor as claimed in claim 5 in which the material of said mass in said helical space is non-hygroscopic, and at temperatures higher than operating or installation temperatures has characteristics of mobility and adhesiveness, said helical rib element and at least said first-mentioned sheet material being substantially impregnated by material of said mass under initial conditions of sufficient temperature to effect impregnation and adhesion.

8. An insulated conductor as claimed in claim 5 in which there is interposed between the rubber jacket and said first-mentioned sheet material a tough, resilient stretchable coating of a material of the lacquer class, said coating being bound to the rubber jacket and reinforcing the latter mechanically against the winding pressure of said helical rib element.

9. An insulated conductor as claimed in claim 5 in which there is interposed between the rubber jacket and the first-mentioned sheet material a means acting to provide for relative ease of slippage, as during bending, between the jacket and said first-mentioned sheet material, thereby, during bending, to permit relative self-accommodation, according to the radius of bending, between said conductor and rubber jacket as one unit and said first-mentioned sheet material with said rib element, insulating mass and overlying sheet material as another unit.

10. An insulated conductor as claimed in claim 5 in which there is interposed between the rubber jacket and the first-mentioned sheet material a coating of a material of the lacquer class, said coating being bound to said rubber jacket and being pliant and stretchable therewith to provide relative ease of slippage between the jacket and said first-mentioned sheet material, thereby, during bending, to permit relative self-accommodation, according to the radius of bending, between said conductor and rubber jacket as one unit and said first-mentioned sheet material with said rib element, insulating mass and overlying sheet material as another unit.

11. An insulated conductor as claimed in claim 5 in which there is interposed between

the rubber jacket and the first-mentioned sheet material a coating of a material of the lacquer class, and having at its surface or projecting therefrom and substantially uniformly distributed small particles or flakes of non-conductive material, thereby, during bending, to permit relative self-accommodation, according to the radius of bending, between said conductor and rubber jacket as one unit and said first-mentioned sheet material with said rib element, insulating mass and overlying sheet material as another unit.

12. An insulated plural-conductor construction of the character described comprising an outer tearable sheath or jacket encasing a plurality of conductor structures each comprising a conductor having an insulating and protecting sheathing means that comprises a rib element of substantial thickness and of a material resistant to compression and extending helically and forming an open winding to provide a helical space of a depth commensurate with the thickness of the rib element and insulating and protective means accommodated in said helical space, the rib elements of said conductor structures and their respective insulating and protective means of said helical spaces coacting to resist diminution of the spacing between the axes of said conductor structures within said outer sheath and the valleys formed along said plurality of conductor structures being filled with suitable means including a cord element in at least one valley having substantial tensile strength, whereby it functions as a rip cord to rip lengthwise said outer sheath to expose the plurality of conductor structures, said rib element having a tensile strength so that it may be pulled at its end, upon exposure of the conductor structure, and remove from the latter said means initially accommodated in said helical space.

13. A conductor construction as claimed in claim 12 in which said conductor has, underlying said rib element and the means accommodated in said helical space, covering means that comprises a jacket of rubber having a pliant coating carrying coloring or pigment means whereby, upon pulling off of the rib elements of the several conductor structures with their respective insulating and protective means, the conductors may be by the coloring or pigment means distinguished from one another.

14. In a method of sheathing and insulating an electrical conductor, the steps which comprise forming a conductor core structure by applying a rubber jacket to a conductor and by applying over the rubber jacket a non-metallic material to give the rubber of the jacket ease of slippage, applying a sheet-like material next to said last-mentioned material and about said core structure for the reception thereon of subsequently applied insulating and sheathing elements and to carry the latter for relative ease of slippage with respect to said rubber jacket, winding helically about said sheet material a rib element of substantial thickness and of a material resistant to compression and at a long lay to provide a helical space between adjacent turns and at sufficient tension so that the turns thereof resist displacement, compacting into said helical space a pliant non-flowable insulating mass, applying a sheet material over said helical rib element and said insulating mass to cover the latter and building over said last-mentioned sheet material a non-metallic casing to back up

and reinforce said last-mentioned sheet material in confining said pliant non-flowable helical mass.

15. In a method of sheathing and insulating an electrical conductor, the steps which comprise forming a conductor core structure by applying a rubber jacket to a conductor, applying a sheet-like material about said core structure, winding helically thereabout a rib element of substantial thickness and of a material resistant to compression and at a long lay to provide a helical space between adjacent turns and at sufficient tension so that the turns thereof resist displacement, compacting into said helical space and in heated condition a mass of insulating material that is pliant and non-flowable at operating or installation ranges of temperature and that is relatively flowable and has adhesive qualities when in heated condition, thereby to flow and compact said material into said helical space and to cause it to bind said sheet material and said rib element together, applying a sheet material thereover and while said mass in said helical space is still in heated condition, thereby to cause said second sheet material to become bound to said helical mass, and building thereover a non-metallic casing.

16. In a method of sheathing and insulating an electrical conductor, the steps which comprise forming a conductor core structure by applying a rubber jacket to a conductor, applying an impregnable sheet material externally of said core structure, winding thereover a rib element of substantial thickness and of a non-metallic material resistant to compression and at a long lay to provide a helical space between adjacent turns, compacting into said helical space and in heated condition a mass of insulating material that is pliant and non-flowable at operating or installation temperatures and that is relatively flowable when in heated condition beyond said temperature ranges to thereby impregnate and bind said sheet material, applying thereover an impregnable sheet material under temperature conditions high enough to cause impregnation thereof by the material of said mass, and building thereover a non-metallic casing.

17. In a method of sheathing and insulating an electrical conductor, the steps which comprise forming a conductor core structure by applying a rubber jacket to a conductor, applying and binding to the rubber jacket a relatively thin tough stretchable coating to reinforce the rubber of the jacket, winding helically thereabout a rib element of substantial thickness and of a non-metallic material resistant to compression at a long lay to provide a helical space between adjacent turns and at sufficient tension so that the turns thereof resist displacement, compacting into the helical space a pliant non-flowable insulating mass, and applying thereover non-metallic sheathing means to form a non-metallic casing to coat with said helical rib element in confining said insulating mass in said helical space.

18. In a method of sheathing and insulating a conductor the steps which comprise vulcanizing a rubber jacket about a conductor, applying to the rubber jacket while still retaining heat from the step of vulcanizing a heat-responsive coating material that is set by the heat content of said jacket, winding thereabout a rib element helically at a long lay to provide a helical space

5 between adjacent turns, compacting into said helical space and in heated condition a protective insulating medium that is pliant at operating or installation temperatures and that is relatively flowable when in heated condition at temperatures insufficient to over-vulcanize the rubber of said jacket, and applying thereover non-metallic confining and insulating casing means.

19. An insulated conductor construction of the character described, in combination, a conductor core structure comprising a conductor and a rubber jacket, said core structure being enveloped by a built-up insulating and protective sheathing structure that comprises a rib element of substantial thickness and of a material resistant to compression extending helically about said core structure at a long lay to provide a helical space between adjacent turns, with a mass of insulating material that is tough, pliant and non-flowable at operating and installation ranges of temperature and that has characteristics of mobility and adhesiveness at higher temperatures compacted into said helical space, there being interposed between said core structure and said insulating material a layer of non-conductive material adhesively bound to said mass of insulating material under initial conditions of sufficient temperature of the latter to effect adhesion between the two, said layer of non-conductive material mechanically separating said insulating material from said core structure and thereby preventing the former from adhering to the latter and thereby permitting relative movement, as during bending, between said core structure and said insulating and protective sheathing structure, and an outer flexible non-metallic sheathing impregnated with moisture-proofing and fire-resistant saturants and having a sheet material along its inner face to resist flow of said saturants inwardly from said outer sheathing, and a layer of non-conductive material covering over and bound to said mass of insulating material and preventing the latter from adhering to said sheet material and thereby permitting relative movement, as during bending, between said outer sheathing and said insulating and protective sheathing structure.

20. An insulated conductor construction as claimed in claim 1 in which said helical tape element extends helically about said core structure at substantially the same pitch as said rib element, there being binding means binding said helical tape element to said helical sheathing means and to said helical rib element, whereby said helical tape element is removed with and as part of the unit formed by said helical sheathing means and said rib element when the latter is pulled.

21. An insulated conductor construction as claimed in claim 1 in which said helical tape element extends helically about said core structure at substantially the same pitch as said rib element, there being interposed between said removable covering sheath means and said helical sheathing means a tape element that extends helically about said helical sheathing means and said helical rib at substantially the pitch of the latter, there being binding means binding both of said helical tape elements to said helical sheathing means and to said helical rib element, whereby both of said helical tape elements are removed with and as part of the unit formed by said helical sheathing means and said rib element when the latter is pulled.

22. In a method of sheathing and insulating 75 a conductor, the steps which comprise jacketing

a conductor with insulating means that comprise rubber, thereby to form a conductor core structure, winding helically about the latter an impregnable tape element, winding helically thereabout a rib element of substantial thickness and of a non-metallic impregnable material resistant to compression and at a long lay to provide a helical space between adjacent turns and at sufficient tension so that the turns thereof resist displacement, drawing the resultant structure in an axial direction and during its movement causing said helical rib element to pick up and move with it a plastic material that is capable of impregnating the materials of said tape element and of said rib element and that is pliant at conductor-operating temperatures, drawing the structure through a device having a restricted throat to compact the plastic material into the helical space and press it against said tape element and said rib element to impregnate them and to become bound thereto, and applying thereover flexible non-metallic sheathing means to confine said plastic pliant material in said helical space.

23. In a method of sheathing and insulating a conductor, the steps which comprise jacketing a conductor with insulating means that comprise rubber, applying thereto a wax-like temperature-responsive coating, applying thereover an impregnable sheet-like material, winding helically thereabout a rib element of substantial thickness and at a long lay to provide a helical space between adjacent turns, compacting into said helical space and in heated condition a mass of insulating material that is pliant and non-flowable at operating or installation ranges of temperature and that is relatively flowable when in heated condition to thereby cause said heated insulating material to impregnate said sheet material from the outer face of the latter and to become bound thereto and by its heat to affect said wax-like temperature-responsive coating material to impregnate said sheet material from the other face thereof, and applying thereover flexible non-metallic sheathing means to confine said pliant insulating material in said helical space.

CHARLES W. ABBOTT.
